UNITED STATES PATENT OFFICE.

FRED L. SMITH AND PETER O. GAUDREAU, OF BURLINGTON, VERMONT.

ELECTRIC MAIL-BOX.

1,119,463.

Specification of Letters Patent. Patented Dec. 1, 1914.

Application filed September 22, 1913. Serial No. 791,184.

To all whom it may concern:

Be it known that we, FRED L. SMITH and PETER O. GAUDREAU, citizens of the United States, residing at Burlington, in the county of Chittenden and State of Vermont, have invented certain new and useful Improvements in Electric Mail-Boxes, of which the following is a specification, reference being had therein to the accompanying drawings.

10 This invention relates to a mail box and the principal object of the invention is to provide an attachment for the mail box so that when the mail box is opened to put letters in, a bell will be rung thus indicating 15 that a letter has been placed in the box.

Another object of the invention is to so construct the contacts that the bell will be given a short ring and not ring continually.

With these and other objects in view, this 20 invention consists of certain novel combinations, constructions and arrangements of parts as will be hereinafter fully described and claimed.

This invention is illustrated in the accompanying drawings, wherein:

Figure 1 is a perspective view of the improved mail box. Fig. 2 is an elevation looking at the rear of the supporting board. Fig. 3 is a vertical sectional view through 30 the mail box. Fig. 4 is a transverse sectional view through the mail box. Fig. 5 is a view looking at the inner face of the door. Fig. 6 is a fragmentary sectional view through the front door and a corner of the mail box and shows the contacts carried by the door and mail box. Fig. 7 is a fragmentary sectional view through the upper portion of the mail box. Fig. 8 is a perspective view of the contact strip which is secured to the 40 front wall of the mail box. Fig. 9 is a sectional view showing the manner in which the contact strip shown in Fig. 8 is insulated from the front wall. Fig. 10 is a fragmentary sectional view through the lower portion of the mail box. Fig. 11 is a fragmentary sectional view showing the manner in which the plate mounted in the bottom of the mail box is insulated from the bottom 50 of the box. Fig. 12 is a view showing a number of mail boxes secured to the wall in the vestibule of an apartment house. Fig. 13 is a diagrammatic view of the electric circuit for one of the mail boxes shown in Fig. 12. Fig. 14 is an enlarged view of the upper left-hand corner of the front wall

shown in Fig. 13. Fig. 15 is a section taken along line 15—15 in Fig. 14.

The mail box in the drawings has been shown secured to the back board 15 which is supported by a standard 16. This back 60 board may be mounted, as shown, or if desired may form a portion of the front door, or of any part of the woodwork of a house. The electric bell 17 may be mounted directly upon the back board, as shown in the drawings, or if desired the bell and switch 18 65 can be located in any desired place.

The mail box 19 is secured to the back board 15 and is provided with a bottom 20 and front wall 21 with which electric contact members are connected; as will be brought out further on in the specification. The front wall is provided with a lower opening which is closed by a hinged door 22, the lower opening being provided so that 75 mail can be taken from the box. An inlet opening is formed in the upper portion of the front wall by cutting a tongue 23 through the front wall and moving the same upwardly, thus forming the inlet opening 80 24 and also forming a lip which guides the letters into the box and forms a stop for the plates 25, which forms a closure for the opening 24.

A metal strip 26 is secured to the front 85 wall 21 by means of the small bolts 27 which pass through openings 28 in the strip 26. Insulating collars 29 are carried by the bolts 27 and hold the strip 26 in spaced relation to the front wall, as shown in Fig. 9. The strip 26 extends vertically in the mail box and has its upper end portion 30 bent inwardly as shown in Fig. 6. This bent end portion 30 extends beneath a tongue 31 carried by the closure plate 25 so that when the closure plate is raised, the contact tongue 31 will be brought into engagement with the upper end of the contact strip 26 and thus an electric circuit formed.

The lower end portion 32 of the strip 26 100 is bent inwardly, as shown, and the end portion 33 is then bent across the lower opening in front of the contact tongue 34 which extends from the door 22. From an inspection of Fig. 4, it will be readily seen that 105 when the door is opened or closed, the tongue 34 will engage the lower end portion 33 of the strip 26, thus causing the electric bell to ring for a short time while the door is being opened or closed. If the door 11

- 2
- is not securely closed, the bell will not ring since the bell only rings for a short time during the opening and closing movement, and, therefore, the electricity will not be wasted.
- 5 One of the wires 35 of the electric circuit is connected with the body portion of the box as shown in Fig. 4, and the second wire 36 is connected with the strip 26 and with a contact plate 37 which is secured to the bottom of the box by means of the bolts 38 and insulated therefrom by means of the insulating collars 39.
- 10 A contact pin 40 is pivotally connected with the bottom of the mail box by means of the brackets 41 and has one end positioned beneath the hooked end portion 37' of the plate 37 and its outer end portion extending through a slot in the front wall beneath the door 22. A lever 42 is hinged to the bottom of the box and has its forward end portion 43 bent upwardly and provided with an opening through which the outer end of the pin 40 passes, as shown in Fig. 1. A tongue is struck from the lever 42 and is bent to form a hook 44 by means of which packages may be suspended beneath the mail box. When a package is placed on the hook this draws the lever downwardly against the tension of the spring 45 and moves the pin 40 upon its pivot so that the inner end of the pin will be brought into engagement with the plate 37 and thus an electric circuit formed so that the bell will ring. This pin 40 is only held in engagement with the plate 37 for a short time since the inner end portion is heavier than the outer end portion, thus causing the pin to return to its normal position when released from the hooked end portion of the lever 42.
- 15 40 A button 46 is mounted upon the block 47 and is connected with the wires forming the electric circuit by means of the wires 48 and 49, so that when desired, the bell may be rung by means of the button 46. In the form shown in Figs. 12 and 13, the boxes are placed in a row in the vestibule of an apartment house and the buttons 46 are placed beneath the boxes 50.
- 20 This mail box is put in place with the electric bell mounted at a desired point, and with the battery 51 connected with the wires 52 and 53. The box is now ready for use and it will be readily understood from the foregoing description that when the closure plate 25 is raised to place any mail in the box, the contact tongue 31 will be brought into engagement with the end portion 30 of the strip 26, thus causing the bell 17 to ring. It will also be seen that if a package
- 25 is suspended from the hook 44 that the contact pin 40 will be brought into engagement with the plate 37 and the bell will be caused to ring. It will also be seen that when the door 22 is opened to remove the mail, that
- 30 the bell will be caused to ring and this will

indicate that an unauthorized person has opened the door 22. If it is not desired to have the bell ring, the switch 18 can be opened and this will prevent the bell 17 from ringing, since it will break the circuit.

70 The end portion 30 of the contact strip 26 in Figs. 13, 14 and 15 is not curved across the inlet opening, as it is in the form shown in Fig. 5, but is bent away from the front wall as shown in Fig. 15 so that the tongue 48 extending from the closure 25 can pass between the front wall to the free end of the contact strip, as clearly shown in Fig. 14. When the closure 25 is moved inwardly to the dotted line position shown in Fig. 15, the tongue is brought into engagement with the end portion of the strip 26, thus closing the electric circuit. The closure 25 is thickened toward its free edge and is provided with the reduced lip 49 which prevents it from moving upwardly beyond a desired amount. This form of closure is particularly intended for use in connection with the mail boxes which are mounted in the wall of an apartment house, as shown in Fig. 12.

85 What is claimed, is:

1. A mail box comprising a receptacle having its front wall provided with upper and lower openings, closures for said openings hinged to the front wall of said receptacle, contact tongues extending from said closures into said receptacle, a contact strip secured to the inner face of the front wall of said receptacle and insulated therefrom, the upper end portion of said contact strip being bent beneath the contact tongue of said upper closure, and the lower end portion of said contact strip being bent inwardly into said receptacle and being then twisted and carried partially across the lower opening with its free end positioned in the course of travel of the contact tongue of the lower closure, whereby the contact tongue of the lower closure will be brought into engagement with the lower end portion of said contact strip for a portion of the time during the opening of the lower closure.

100 2. A mail box comprising a receptacle, a contact plate secured to the bottom of said receptacle and insulated therefrom, the free end portion of said plate being bent upwardly, a contact pin pivotally connected with the bottom of said receptacle and having one end portion extending beneath the upwardly bent end portion of the plate and having its opposite end portion extending through an opening formed in the front wall of said receptacle, a lever pivotally connected with said receptacle and having its free end portion bent upwardly to extend along the front wall of said receptacle, and provided with an opening through which the upper end portion of said contact pin passes

when said lever is in a raised position, supporting means carried by said lever, and means for normally holding said lever in a raised position.

- 5 3. A mail box comprising a receptacle, provided with inlet and outlet openings, closures for said openings provided with contact tongues, a contact strip insulated from the walls of said receptacle and having its 10 free ends positioned in the course of travel of said contact tongues, a contact plate insulated from the bottom of said receptacle, a contact pin pivotally connected with the bottom of said receptacle, and a supporting 15 lever having its free end provided with an

opening in which the outer end of said pivotally mounted pin is positioned when said lever is positioned in a raised position, whereby said pin may be brought into engagement with said contact plate during a 20 portion of the time said lever is moving to a lowered position, and means for yieldably holding said lever in a raised position.

In testimony whereof we hereunto affix our signatures in presence of two witnesses. 25
